CAN KEY TURNING DEVICE

Charles D. Thompson, Andover, Mass., assignor to Merrimade, Inc., Lawrence, Mass., a corporation of Massachusetts

Application October 20, 1953, Serial No. 387,096

10 Claims. (Cl. 220—52)

This invention relates to apparatus for removing a tear strip from an hermetically sealed can of the type much used in packaging coffee and other products. Such strips are usually formed by scoring a pair of parallel lines around the side of a can, adjacent the flat top thereof, and the top is usually inset to provide a rim around the end of the can. A tongue is usually provided forming a free terminal tip at the end of the tear strip, and usually a slotted key is soldered to the end of the can for use in removing the tear strip.

The key customarily provided with each can is of wire and the head is only slightly larger than the thumb of the user in order to keep manufacturing cost as low as possible. However, because of their small size, such keys tend to be difficult to retain in the fingers, tend to become more difficult to turn as the tear strip accumulates thereon and tend to injure the fingers of the user by causing an indent in the same due to excess pressure.

The principal object of this invention is to provide a new article of manufacture which can be made at extremely low cost, and which can be used to secure a better grip on such keys.

Another object of the invention is to provide a device which can be clamped onto the head of such a key, can be used for turning the key more efficiently and can then be easily removed from the key to be used on another can key.

A further object of the invention is to provide a device which positions the head of a key at the correct initial height above the tear strip and above the can rim or edge and by means of its flat lower edge retains the proper spacing as the key is revolved thereby preventing eccentric accumulation of the tear strip on the key.

Still another object of the invention is to provide an article in which it is easy to insert the head of a key, in which the head is tightly held and from which the head can be easily disengaged when the tear strip of a can has been removed.

A still further object of the invention is to provide an inexpensive key clamp or holder, preferably made of only two pieces of sheet material, plus a hollow rivet, the clamp having integral stop means for registering the plates, an integral finger abutment to aid in opening the clamp and spring pressure means for clamping the head of the key in place therein.

In the drawing

Fig. 1 is a front view of a preferred embodiment of the invention in use on a typical can;

Fig. 2 is a view similar to Fig. 1, showing the device in open position;

Fig. 3 is an end view of the device on an enlarged scale;

Fig. 4 is a view similar to Fig. 3 on line 4—4 of Fig. 1 and

Fig. 5 is a view similar to Fig. 1 of a modification of the invention.

As shown in the drawing C is a typical, hermetically sealed can, having a tear strip S, the strip S having a free terminal end 21 which may be in the form of a tapered

2

tongue. Can C has a top end 22, which is flat, as well as a peripheral rim 23 which usually defines a circle, but may assume other shapes such as oval or rectangular with curved corners.

5 A key K, usually of bent wire, is ordinarily soldered to the central portion of the top or bottom end of can C, and is provided with a key head 24, key shank 25 and key slot 26 all in a well known manner. When a key such as K has heretofore been used to open a can such as C, the terminal end 21 of the tear strip S has been inserted in key slot 26 and the key head 24 has been spaced about a quarter of an inch above the rim 23 of the can. It has required considerable pressure between the thumb and forefinger of the user to start the severing of the tear strip 10 and progressively greater pressure to turn the key as the spiralled turns of the tear strip accumulated on the key shank 25 during the traverse around the can C. Often times, the user has been unable to keep the spiral turns in overlying position and once the key shank has slipped out from beneath the same, it has proved extremely difficult to remove the remainder of the tear strip.

15 As shown, this invention provides a separable key handle, key holder, or key clamp A for providing increased leverage, an accurate turning guide and a comfortable grip in combination with a key such as K or a key of any similar shape and type. Key holder A includes a pair of elongated plates, preferably of sheet material such as pressed steel, one of which is called herein the cover plate or pivoted plate 27 and the other of which is called herein the body plate or recessed plate 28. The elongated plate 28 includes a substantially oval socket or recess 31 in the inner surface 29 thereof, for receiving the head portion 24 and the adjacent shank portion of a key K and the recess 31 is spaced at the correct distance above 20 the flat, straight, lower edges 32 and 33 of plates 27 and 28 to cause said lower edges to ride on the rim 23 of can C when the device is turned.

25 The recess 31 is preferably annular with its outer perimeter 17 large enough to accommodate large sized key heads and its inner perimeter 18 small enough to accommodate the inside perimeter of the head of small sized keys such as 24. The oval or elliptical raised portion 19, within recess 31, thus tightly engages small keys and recess 31 itself tightly engages large keys.

30 Pivot means 34 is provided at one end of plates 27 and 28 of key holder A for joining the same together, and permitting oscillation thereof in parallel planes. Preferably, pivot means 34 is a hollow tubular rivet or eyelet 35 having an opening 36 whereby the device may be hung on a nail when not in use. Preferably, stop means 37 is also provided on at least one of the plates 27 or 28 to cause the plates to register with their outer edges flush when the device is pivoted or oscillated to a closed position. Stop means 37 may be an integral tab 38 of U-shaped cross section formed in one of the plates and extending over the other plate, as best shown in Fig. 3. Preferably also, a finger abutment 40 is provided along part of the top edge 41 of a plate such as 27 to assist the user in opening the plates to detach or insert a key 35 head 24.

35 Preferably, at least one of the plates of key holder A such as plate 27 is formed of inherently resilient material and the other plate 28 is provided with an integral tab 30 bent around the adjacent end of plate 27 to clamp 40 the said ends together. Thus the pivot means 34 presses one pair of plate ends together and the tab 30 presses the other pair of plate ends together while the central portion of plate 27 is spring pressed against key head 24 while the plates are closed. Keys made of wire of various 45 diameters, within a limited range, may thus be held tightly in key holder A with plate 27 flexing to press them firmly into the recess 31 of plate 28.

Preferably the end edges 71, 72 and 73 and 74 of plates 27 and 28 are tapered, as shown, whereby the integral tab 30 not only serves as a clamping member, but also serves as a stop for the edge 72 of plate 27 in addition to, or in place of, stop means 37.

As shown in Fig. 5, a key holder B may be provided having a pair of plates 50 and 51, a pivot 52, and a recess 53 for the head of a key K. The finger abutment 54 may be more elongated than in key holder A, and may be formed by turning back an extension of the upper edge of plate 50 upon itself. The stop member 55 may also be centrally disposed and formed by turning back the lower edge of plate 51 upon itself, thereby also clamping the lower edges of the plates 50 and 51 together. Stop member 55 thus supplements the clamping action and stopping action of the integral tab 58 which is otherwise similar to tab 30 of the key holder A. An opening 57 is provided in stop member 55 to accommodate the shank of a key K.

It will be apparent that various changes may be made in the construction of the invention described and illustrated herein without departing from the scope of the invention, the forms herein being merely preferred embodiments thereof.

I claim:

1. As an article of manufacture a separable handle for turning and guiding a can key with relation to a tear strip type can, said handle comprising a substantially flat, elongated body plate of greater width and length than the width and length of the head portion of a can key and having a straight, lower, longitudinal edge, said body plate having a substantially oval socket formed intermediate of the width and length of one flat face thereof for receiving the head and adjacent shank portion of a can key and positioning the key with its shank projecting perpendicularly from an intermediate point along the lower edge of said body and a substantially flat, elongated cover plate, pivoted at one end to the adjacent end of said body plate to turn in a plane parallel therewith and adapted to retain the head portion of a can key in said socket when said cover plate is turned co-extensive with, and flatwise against, said plate body.

2. A combination as specified in claim 1 wherein the straight lower longitudinal edge of said plate body is spaced a predetermined distance from said socket for causing said lower edge to be supported and guided on a can rim when a key, engaged in said socket, is engaged with a can tear strip.

3. A combination as specified in claim 1 wherein said substantially oval socket is annular with a central raised portion having a face co-planar with the adjacent flat face of the plate body, the outer periphery of said annular socket tightly fitting around the outer periphery of large annular key heads and the inner periphery of said annular socket tightly fitting within the inner periphery of small annular key heads.

4. A combination as specified in claim 1 wherein said plates are of resilient material and adapted to be slightly flexed centrally of the length thereof proximate said socket for retaining the head portions of can keys of various thickness of material in said socket by inherent resiliency.

5. A combination as specified in claim 1 plus an integral U-shaped tab extending along an edge of one of said flat

plates proximate the free end thereof, said tab being bent toward the other plate and then bent back upon itself to receive and stop said other plate when said plates are co-extensive with each other.

- 5 6. A separable handle for use in guiding and turning the key of sealed, sheet metal, food containers of the type having a tear strip parallel to a rim thereof, said handle comprising an elongated flat body plate of greater area than the area of the head portion of a key and having 10 a socket centrally disposed longitudinally in the inside flat face thereof for receiving and retaining the head and adjacent shank portion of a key flatwise therein with the shank of the key projecting laterally therefrom; a flat cover plate substantially co-extensive with the area 15 of said body plate and pivoted thereto at one end thereof to swing in a plane parallel to the plane of said body plate, said cover plate having a flat inside face adapted to engage the head and adjacent shank portion of a key in said socket and hold the same therein when flatwise 20 thereagainst and an integral U-shaped tab on said body plate extending into the pivot path of the cover plate proximate the non pivoted end of said cover plate to embrace and stop said plate in registration with the body plate.
- 25 7. A combination as specified in claim 6 wherein said plates are of resilient sheet metal and said tab forms a resilient U-shaped clamp with said body plate for resiliently clamping said cover plate in closed position.
8. A combination as specified in claim 6 wherein the 30 lateral edges of said plates are tapered to converge downwardly and said U-shaped integral tab is formed in the free lateral edge of one of said plates to receive and stop the free lateral edge of the other plate in registration.
9. A can opener for strip sealed cans comprising a 35 can key having a looped head, a substantially flat body plate of greater width and length than said key head, said body plate having a centrally disposed socket therein, equal in depth to the thickness of said key head, and arranged to receive said key head with the key shank projecting outwardly in the plane of said body plate from centrally of the length thereof and a cover plate, pivoted to said body plate at one end thereof, to swing parallel thereto, said cover plate being adapted to lock said key head in said socket when swung alongside said body plate.
- 40 10. A combination as specified in claim 9 wherein the opposite ends of said body plate and said cover plate are tapered, said plates are of resilient material and a U-shaped tab extends along the tapered free end of one of said plates for embracing and stopping the tapered free end of the other said plate in closed position.
